Patented Aug. 29, 1916.

UNITED STATES PATENT OFFICE.

MATTIE R. HATFIELD, OF WICHITA, KANSAS.

SHOE-CLEANING ATTACHMENT FOR AUTOMOBILES, &c.

1,196,453.

Specification of Letters Patent. Patented Aug. 29, 1916.

Application filed April 28, 1916. Serial No. 94,152.

To all whom it may concern:

Be it known that I, MATTIE R. HATFIELD, a citizen of the United States, residing at Wichita, in the county of Sedgwick and State of Kansas, have invented certain new and useful Improvements in Shoe-Cleaning Attachments for Automobiles, &c.; and I hereby declare that the following is a full, clear, and exact description thereof, reference being had to the accompanying drawings, which form part of this specification.

This invention is a novel improvement in shoe cleaning or wiping devices for automobiles; and its object is to provide a simple attachment which can be readily secured to and beneath the step, or running board, of an ordinary automobile; and when it is desired to use the cleaner it can be readily projected from beneath the step into position for use; and after use it can be readily pushed back out of the way under the step, and be concealed when not in use and while the vehicle is being transported.

The attachment is efficient, sightly, and compact.

I will explain the invention as illustrated in the accompanying drawings, which illustrate one practical embodiment thereof; and will set forth in the claims the essential features of the invention and combinations of parts for which protection is desired.

In the drawings: Figure 1 is a view showing the position of the device when attached to an automobile step. Fig. 2 is an enlarged top plan view of the attachment detached, with the drawer open and brush ready for use. Fig. 3 is a side view of the attachment as applied to a step, with the drawer open. Fig. 4 is a longitudinal section through the attachment Fig. 2 on line 4—4, closed. Fig. 5 is a transverse section on line 5—5 Fig. 4. Figs. 6 and 7 are details.

The attachment comprises an outer casing 1, preferably made of sheet metal and open at top and front and closed at back and sides; the sides have top flanges 1^a, and front flanges 1^b. The sides are also provided with longitudinal slots 1^c for a purpose herein-after explained. In the bottom of the box may be one or more openings 1^e. This casing is adapted to be secured to and under the running board or step S of an automobile, or other vehicle, as indicated in Fig. 1; and may be fastened thereto in any suitable way, preferably by means of hanger straps at front, and by bolts or screws 2 extending

through the running board and through openings 1^f in the flanges 1^a, if desired. The hanger straps are attached to the front flanges 1^b and have upper horizontal parts 3 adapted to engage and overlie the front upper edge of the step, as shown in Fig. 4 and the vertical portions 3^a of these hangers may be riveted to the flanges 1^b so as to permanently secure same thereto. By means of 65 these hangers the front end of the casing, (whereupon the greatest strain is exerted when the brush is used) is securely suspended from the step. The upper ends 3 of the hanger may if desired be let into kerfs or 70 notches in the top step; and they can be conveniently fastened to the step by means of screw-bolts 3^c tapped through brackets 3^d secured to the sides of the box beneath flanges 1^a and adjacent the front flanges 1^b 75 (see Figs. 3, 5 and 6) so that the screws can be conveniently manipulated.

If desired the lower ends of the hangers 3 may be extended rearwardly beneath the lower ends of the flanges 1^b, as indicated at 80 3^e, and these extended portions 3^e may be connected to the sides of the box by means of angle-irons 3^g riveted to the parts 3^e and adjacent sides of the box as shown in Fig. 6.

Slidably mounted within the casing 1, so 85 as to telescope therewith, is a box or drawer 4 which is preferably made of sheet metal and may be closed at front and rear. Preferably a plate 4^a is attached to the front end of drawer 4 and extends sufficiently to project over and cover the end flanges 1^b of the casing when the drawer 4 is closed and said plate may be exteriorly finished or decorated in any desired manner.

The drawer 4 is preferably made of sheet 95 metal, and its front edge may serve as a scraper. Its sides are preferably concaved or notched as at 4^b near its front end, and between such concave portions 4^b, and extending transversely of the drawer, is a 100 brush or brushes 5 which may be of any suitable kind and placed in the drawer between the concave portions 4^b of the sides thereof, but the brush need not extend more than half the length of the drawer and, if desired, it can be removably secured in the drawer by any suitable means. As shown the drawer is provided with a transverse partition 4^e against which the inner edge or side of the brush lies, the brush being held 105 between the partition 4^e and the front end of the drawer. As shown the brush 5 is a 110

concave brush having a wooden back 5^a adapted to easily fit in the front compartment of the drawer. The brush may have openings in it so as to permit dirt to work out through the brush and escape through the opening 1^e if desired, and its sides may be slightly tapered, as shown, so that dirt can work down and pass out through the opening 1^e. Any other suitable kind of brush or brushes may be used.

The drawer 4 is preferably made slightly narrower at bottom than at top so that if any dirt should fall out of the drawer into the casing it would work down and escape through openings 1^e, and the drawer not become chocked in the casing.

To prevent the drawer being entirely withdrawn from the casing it may be slightly retained therein by any suitable means preferably by thumb-bolts 6 which are adapted to pass through the slots 1^e in the sides of the casing and through apertures in the sides of the drawer and have reduced threaded portions 6^a that engage nuts 6^b inside the drawer, see Figs. 2 and 7. The bolts 6 are shouldered so that they can tightly engage with the nuts without binding in the slots 1^e. If desired sleeve rollers 6^c may be placed on the enlarged portions 30 of the bolts between their heads and threaded ends, so that these rollers will act as guides in the slots 1^e, and will not be bound against rotation by the tightening of the bolts 6.

35 The drawer may be provided with any suitable means to hold the drawer in closed position, when it is not desired to use same: a catch 7 being indicated adapted to engage a keeper 7^a attached to the step.

40 It will be seen that the device can be readily attached to the step of an automobile in the most convenient position for use by persons entering or leaving the same. When it is desired to use the brush the catch 45 7 is disengaged and the drawer drawn outward to the limit permitted by the slots 1^e (see Figs. 2 and 3) which will permit persons to clean their shoes by drawing them across the brush, longitudinally of the step. 50 After the shoes are cleaned the drawer can be pushed inward by the foot, and the catch will hold the drawer closed until it is again desired to use the brush.

What I claim is:

55 1. A brush holding attachment for automobiles and the like comprising a casing adapted to be suspended beneath and from a vehicle step or running board, a drawer slidably mounted in said casing and having its sides notched, a brush in the drawer between the notched portions of the sides thereof whereon shoes can be wiped by drawing same transversely across the drawer, and means to retain the drawer in the casing.

60 2. A brush holding attachment for auto-

mobiles and the like comprising a casing adapted to be suspended beneath and from a vehicle step or running board and having longitudinal slots in its sides and an opening in its bottom, a drawer slidably mounted in said casing and having an opening in its bottom adapted to register with the opening in the casing when the drawer is closed, a cleaning device in the drawer, and means attached to the drawer to engage said slots 75 and retain the drawer in the casing.

3. A brush holding attachment for automobiles and the like comprising a casing adapted to be suspended beneath and from a vehicle step or running board and having 80 longitudinal slots in its sides and an opening in its bottom, a drawer slidably mounted in said casing and having a plate on its front end adapted to cover the front of the casing when the drawer is closed, the sides 85 of the said drawer being notched, a brush in the drawer adjacent and extending between the notched portion of the sides thereof, and means attached to the drawer to engage said slots and retain the drawer in the 90 casing.

4. A brush holding attachment for automobiles and the like comprising a metallic casing having hanger straps adapted to engage the front edge of the step and suspend 95 the casing therefrom, clamping bolts attached to the casing adjacent the hangers adapted to engage the underside of the step and secure the casing in position, a slideable drawer mounted in said casing, a cleaning 100 device in the drawer, means for limiting the withdrawal of the drawer from the casing, and means for holding the drawer in closed position.

5. A brush holding attachment for automobiles and the like comprising a metallic casing having slots in its sides, hanger straps attached to the front of the casing and adapted to engage the front edge of the step and suspend the casing therefrom, a slideable 105 drawer mounted in said casing, a brush secured in the drawer, means attached to the drawer and engaging the slots in the casing for limiting the withdrawal of the drawer from the casing, and means for holding the 110 drawer in closed position.

6. A brush holding attachment for automobiles and the like comprising a metallic casing having front and side flanges and slots in its sides, hanger straps attached to the front flanges of the casing and adapted to engage the front edge of the step and suspend the casing therefrom, a slideable drawer mounted in said casing having notched sides, a brush secured in the drawer intermediate 120 the said notched sides, means engaging the slots for limiting the withdrawal of the drawer from the casing, and means for holding the drawer in closed position.

7. A brush holding attachment for auto- 130

mobiles and the like comprising a casing having flanged sides and front ends, and longitudinal slots in its sides; clamp plates attached to the front flanges of the casing adapted to hang over the edge of the step and suspend the front edge of the casing thereunder, bolts attached to the casing adjacent the clamps to secure the casing in place, a drawer slidably mounted in said 10 casing and having a front compartment, the

sides of this compartment being notched, bolts transfixing the slots and engaging the sides of the casing and secured to the sides of the drawer to retain the drawer in the casing, a brush in said compartment, and means for retaining the drawer in closed position. 15

In testimony that I claim the foregoing as my own, I affix my signature.

MATTIE R. HATFIELD.
